(**) Term: **14 Years**

(57) **CLAIM**

(21) Appl. No.: **29/309,683**

The ornamental design for a member pressing switch contact,
as shown and described.

(22) Filed: **Sep. 26, 2008**

DESCRIPTION

(30) **Foreign Application Priority Data**

Mar. 27, 2008 (JP) ..... D 2008-007696

FIG. 1 is a top perspective view of a member pressing switch contact showing our new design;

(51) **LOC (9) Cl.** 13-03

FIG. 2 is a a bottom perspective view thereof;

(52) **U.S. Cl.** D13/173

FIG. 3 is a front elevational view thereof;

(58) **Field of Classification Search** D13/173;

FIG. 4 is a rear elevational view thereof;

200/400, 407, 410, 443, 447, 449, 502, 512,

FIG. 5 is a left side view thereof;

200/517, 534, 238, 275, 292

FIG. 6 is a right side view thereof.

See application file for complete search history.

FIG. 7 is a top plan view thereof;

(56) **References Cited**

FIG. 8 is a bottom plan view thereof; and,

U.S. PATENT DOCUMENTS

FIG. 9 is a cross-sectional view taken along the line of
IX—IX of FIG. 3.
